US0D1047722S

(12) **United States Design Patent** (10) **Patent No.:** **US D1,047,722 S**
(45) **Date of Patent:** **** Oct. 22, 2024**

(54) **TAPE MEASURE**

(71) Applicant: **Milwaukee Electric Tool Corporation**,
Brookfield, WI (US)

(72) Inventors: **Kyle C. Anderson**, Wauwatosa, WI
(US); **Grant T. Squiers**, Cudahy, WI
(US)

(73) Assignee: **Milwaukee Electric Tool Corporation**,
Brookfield, WI (US)

(**) Term: **15 Years**

(21) Appl. No.: **29/868,641**

(22) Filed: **Dec. 9, 2022**

Related U.S. Application Data

(62) Division of application No. 29/754,953, filed on Oct. 15, 2020, now Pat. No. Des. 974,199, which is a division of application No. 29/673,926, filed on Dec. 18, 2018, now Pat. No. Des. 902,060.

(57) **CLAIM**

The ornamental design for a tape measure as shown and described.

DESCRIPTION

FIG. 1 is a perspective view from below of an embodiment of the claimed design;

FIG. 2 is a top view of the claimed design of FIG. 1;

FIG. 3 is a bottom view of the claimed design of FIG. 1;

FIG. 4 is a right side view of the claimed design of FIG. 1;

FIG. 5 is a left side view of the claimed design of FIG. 1;

FIG. 6 is a front side view of the claimed design of FIG. 1;

FIG. 7 is a rear view of the claimed design of FIG. 1;

FIG. 8 is a perspective view from below of an embodiment of the claimed design;

FIG. 9 is a top view of the claimed design of FIG. 8;

FIG. 10 is a bottom view of the claimed design of FIG. 8;

FIG. 11 is a right side view of the claimed design of FIG. 8;

FIG. 12 is a left side view of the claimed design of FIG. 8;

FIG. 13 is a front side view of the claimed design of FIG. 8; and,

FIG. 14 is a rear view of the claimed design of FIG. 8.

The ornamental design which is claimed is shown in solid lines in the drawings. The broken lines in the drawings are for illustrative purposes only and form no part of the claimed design.

1 Claim, 10 Drawing Sheets
